UNITED STATES PATENT OFFICE.

FRANK B. DAVIDSON, OF MARSEILLES, ILLINOIS, ASSIGNOR TO NATIONAL BISCUIT COMPANY, OF NEW YORK, N. Y., A CORPORATION OF NEW JERSEY.

CARTON.

1,311,325.

Specification of Letters Patent. Patented July 29, 1919.

Application filed October 10, 1917. Serial No. 195,677.

To all whom it may concern:

Be it known that I, FRANK B. DAVIDSON, a citizen of the United States, residing at Marseilles, in the county of La Salle and 5 State of Illinois, have invented new and useful Improvements in Cartons, of which the following is a specification.

This invention relates to foldable boxes or cartons such as are made of cardboard or 10 the like and designed to receive bakery and like products.

Among the objects of my invention is to improve the kind of box or carton referred to in the several particulars as will herein- 15 after more fully appear, and to provide, in particular, a relatively shallow, foldable box adapted to have packed therein relatively narrow bakery products, such as sugar wafers, more commonly known as Nabiscos.

20 A further object of my invention is to provide an improved form of locking means for the end flaps of the box, which locking means is particularly adapted for boxes of the shallow type.

25 A still further object of my invention is to provide a lining sheet of waxed or like paper for the box and fold such sheet in such a manner that it is held from displacement in the box by having an interfolded 30 connection with the end flaps of the box.

The invention also relates to the blank from which said carton is made, and consists further in the matters hereinafter described and more particularly pointed out 35 in the appended claims.

In the accompanying drawings—

Figure 1 is a top plan view of a cut and scored blank from which a box or carton embodying the features of my invention is 40 formed;

Fig. 2 is a like plan view of a lining sheet scored in accordance with my invention and which sheet is used in my improved box;

Fig. 3 is a perspective view of a box set 45 up from the blank shown in Fig. 1, the lid or cover of the box being shown in open position;

Fig. 4 is a perspective view of said box, showing two of the flaps at one end of the 50 box swung open and the adjacent portion of the lining sheet spread out to show the manner in which it folds between the end flaps of the box;

Fig. 5 is an elevational view of one end of the box, the lid or cover being shown in 55 substantially closed position;

Fig. 6 is a transverse sectional view taken on line 6—6 of Fig. 4;

Fig. 7 is a longitudinal sectional view taken on line 7—7 of Fig. 4; and 60

Fig. 8 is a sectional view taken on line 8—8 of Fig. 5.

In the drawings, 10, in Fig. 1, designates a blank in flat form, from which my box or container is formed, and, as shown, said 65 blank is substantially rectangular in shape and is made from a sheet of relatively stiff material, such as paper-board, cardboard, or the like. Said blank 10 is divided by a plurality of substantially parallel fold or 70 score lines 11, 11 into a plurality of integral parallel sections 12, 13, 14, 15, and 16. The section 13 forms the lid or cover of my improved box, while the section 12 forms the marginal flap on the longitudinal free edge 75 of said lid. The section 15 forms the bottom wall of the box, and the sections 14 and 16 form the side walls thereof. The section 14 is provided at each end thereof with a section 17, divided from the section 14 by 80 a suitable score or fold line 18, arranged at right-angles to the score lines 11 of said section 14 and extending across the same. Each section 17 is provided with a section 19, divided from the section 17 by a score line 85 20, which is a continuation of the associated score line 11 of said section 14. In the flat blank the sections 19 are located at the ends of the lid section 13 and are separated from said section 13 by slits or lines of severance 90 21 in alignment with the score lines 18. The bottom section 15 is provided at each end thereof with an integral section 22, divided from said section 15 by a score or fold line 23 forming a continuation of the associated 95 score line 18. The section 16 is provided at each end thereof with an integral section 24, divided from said section 16 by a score line 25 forming a continuation of the associated score line 23. When the blank is set 100 up to form the box, the sections 17, 22, and 24 at the ends of the box overlap and form the end flaps thereof, while the sections 19 extend into the box beneath the lid or cover 105 13, as clearly shown in Figs. 3 and 4 and 6 to 8, inclusive, of the drawings,

To lock the end flaps together, when the box or container is set up from the blank shown and described, the sections 17 and 24 at each end of the box are provided with 5 interlocking parts, which will now be described in detail. Each end flap 17 is provided at its free end with a locking tongue 26 having a curved edge. The portion of the flap 17 inside of the locking tongue 26 10 is cut away to provide an inclined edge 27, which continues inward beyond the base of the tongue 26 to provide a locking shoulder 28. Each end flap 24 is provided, in that edge thereof which forms the upper edge 15 of the flap when the box is set up, with an upwardly opening locking notch 29, preferably V-shaped and having inclined edges 30, 30, which diverge outwardly from the base of said notch. The inclined edge 30 20 adjacent the base of the flap 24 or next to the score line 25 is continued beyond the base of the notch 29 to form a locking part 31, adapted to interlock with the shoulder 28 of the locking tongue 26.

25 To set up the box from the blank shown in Fig. 1, the sections 14, 16 are bent upward on their score lines 11, 11 in an upright position to form the side or front and rear walls of the box. The sections 24, 24 30 are then folded inward to extend between the side walls of the box and form the innermost end flaps thereof, said sections 24, 24 having a length sufficient for that purpose. The sections 22, 22 on the bottom wall 15 35 are then folded upward into an upright position so as to overlap the innermost end flaps 24, 24 on the outside thereof and form the intermediate end flaps of the box. The sections 17, 17 are then folded inward so as 40 to extend between the side walls of the box and overlap the intermediate end flaps 22, 22, and which sections 17, 17 constitute the outermost end flaps of the box. At such time the end flaps 17 are raised upward a 45 sufficient distance so that the locking tongues 26 are in position to be inserted into the locking notches 29, 29, and then said end flaps 17 are pressed downward until the locking shoulders 28 thereof engage the locking parts 31 on the innermost end flaps 24, 24, the intermediate end flaps 22, 22 being 50 cut away as at 22^a to allow the locking tongues 26, 26 to extend behind the innermost end flaps for such locking purposes. 55 The box is now in condition to receive the articles to be packed therein, such as sugar wafers and like bakery products of the relatively narrow type, and after such products are packed in the box, the sections 19, 19 60 are folded downward thereon, whereupon the lid or cover 13 is swung downward and its marginal flap 12 inserted between the packed articles and the side wall 16, the pressure of the packed articles on said marginal flap being sufficient to maintain the

cover 13 in closed position. Said side wall 16 is provided between its ends with a notch 32 opening upward through the upper edge thereof so that the thumb or finger of the person opening the box may readily engage 70 the flap 12 and facilitate the raising or opening of the lid or cover 13.

My improved box or container is especially designed to receive sugar wafers of the kind commonly known as "Nabiscos," 75 and intended to replace the usual tin or other shallow metal box heretofore provided for such purpose. My box or container being relatively shallow, it is necessary that the locking means for the end flaps be of 80 such a nature as to effectively lock said flaps together when the box is set up and in use, and for such purpose it is necessary that the locking tongue have sufficient stock to withstand the strains to which the same is subjected when locking the end flaps together. I have found that by providing an outwardly opening locking notch 29, as shown, 85 the base of the notch may be positioned a little above midway of the end flap in which 90 it is provided, thus enabling the locking tongue 26 to be made substantially the full height of the end flap on which it is provided. From this it follows that the locking tongue 26 may be made large enough to 95 give the same the necessary rigidity and strength required, yet clear the bottom wall of the box when locked with the flaps having the locking notches. By reason of such 100 novel construction I am able to adapt 105 this type of lock to a shallow box and gain an effective locking means for the end flaps, which would be impossible in case the innermost end flap 24 was provided with an inclined locking slot positioned between its 110 upper and lower edges, because in such an arrangement the base or locking end of the inclined slot would necessarily be so close to the bottom edge of the flap that, to have the locking tongue lock therewith would require 115 the locking tongue to be so small, in order to clear the bottom wall of the box, that said tongue would not have sufficient strength to gain an effective lock. On the other hand, to gain an effective lock with an 120 inclined locking slot, the locking tongue, if made large enough to possess the required strength, would then be so large as to contact with the bottom wall of the box or container before it would lock with said slot.

In the foregoing I stated that the bakery products could be packed in the box after being set up from the blank described. That is true, but, in order to maintain the bakery products packed in the box crisp and fresh 125 and prevent the shortening from being absorbed therefrom by direct contact with the walls of the box, I provide a lining sheet for said box, adapted to completely inclose and envelop the bakery products packed 130

therein. In Fig. 2 I have shown said lining sheet as indicated by 33 and flattened out, with the several score lines on which it is folded indicated by dotted lines. As shown 5 in Fig. 2, said lining sheet is rectangular in shape and provided with a substantially centrally arranged section 34, adapted to extend over the inner face of the bottom wall 15 of the box. Said bottom section 34 is 10 bounded on all sides by score or fold lines 35, 36, which divide said bottom section from the remaining portion of the sheet. On opposite sides of said bottom section 34 are sections 37, 38, adapted to extend over 15 the inner faces of the side walls 14, 16 of the box. Fig. 2 is a view looking at that surface of the lining sheet which contacts directly with the products packed in the box, and, as shown, the section 37 is adapted to 20 extend over the inner surface of the front wall 16 of the box, while the section 38 is adapted to extend over the like face of the rear wall 14. The section 39 is integral with the section 37, and is divided therefrom by 25 a score or fold line 40, parallel to the score lines 35 and the edges 41, 42 of said sheet. Said section 39 is bounded at its ends by score or fold lines 43, 43, forming continuations of the score lines 36 and intersecting 30 the edge 41 of said sheet. Said section 39 is further divided within its boundaries by diagonally arranged score lines 44, 44, and when said section 39 is folded on said lines 44 and the line 40, said section extends into 35 the box in the form of a tapered flap from the front wall 16 and over the top of the articles packed therein, but beneath the flaps 19, 19, as shown in Fig. 4. At each end of said section 39 is an integral section 45, 40 bounded on one side by the score line 43, on another side by a continuation of the score line 40, and on the remaining two sides by the edges 41 and 46 of said sheet. When the section 39 is folded on its diagonal score 45 lines 44, the portions of said section 39 between score lines 44 and 43 are folded under said section 39 and carry therewith the sections 45, 45, which at such time extend into the box from the end flaps thereof beneath 50 said sections 39, as clearly shown in Fig. 4. At each end of the section 37 is an integral section 47, divided from the section 37 by a continuation of the score line 36, while being divided from the section 45 by a continuation of the score line 40. Said section 55 47, when the lining sheet is folded with the box, extends between the side walls 14, 16 thereof at the end of the box and is located inside of the innermost end flap 24, as shown in Figs. 4 and 7. The sections 47 prevent the articles packed in the box from 60 contacting with the end walls of said box. At each end of the bottom section 34 is an integral section 48, which is divided from 65 said section 34 by the score or fold line 36 and from the section on each side of said section 48 by continuations of the score lines 35. Said section 48 is divided by a diagonally arranged score line 49 into two equal portions. In folding the section 47 inside 70 of the innermost end flap 24, the section 48 is folded upon itself on said diagonal score line 49, thus giving the folded section a double thickness of sheet material and making the same triangular in shape and extending beyond the end of the box beneath the lower edge of the innermost end flap 24, as clearly shown in Figs. 4 and 7. The section 48 is further divided by score lines 50, 51 arranged at right-angles to each other 75 and meeting in the diagonal score line 49, as shown in Fig. 2. After the section 48 has been folded into the triangular shape shown in Fig. 4, the score lines 35 and 36 are now at the base of the folded section. Said section 80 48 is then folded upward on said score lines and brought to an upright position extending over the outer face of the innermost end flap 24. By folding the section on the diagonal score line 49, the folded edge 90 thereof clears the locking notch 29 in said innermost end flap 24, as illustrated in Figs. 3 and 5. Integral with the section 48 is a section 52, divided from said section 48 by a continuation of the score line 35. Said 95 section 52 is divided from the section 38 by a score line 53, which is a continuation of the score line 36. The remaining two edges of the section 52 constitute the edges of the blank, as shown in Fig. 2. Said section 52 100 is divided by a diagonally arranged score line 54, arranged as shown. After the section 48 has been folded upon itself on its diagonal score line 49 and swung into a position overlapping the innermost end flap 105 24 on the outside thereof, the intermediate end flap 22 is folded into its position overlapping the folded section 48. The remaining portion of the folded section 48 is then bent downward and inward on its score lines 110 50, 51, which at such time are superposed. In folding the section 48 in the manner stated, the section 52 is folded upon itself on its diagonal score line 54 and at the same 115 time bringing the score lines 35 and 53 together. The folded section 52 is folded about the part of the intermediate end flap 22 on the score lines 35, 35 and then downward and inward on the section 45 on the score lines 55, 56, which at such time are one 120 on the other. The end flaps 19, 19 of the box are then folded over the folded sections of the lining sheet, as shown in Fig. 4. Between the end sections 52, 52 (Fig. 2) is a section 57 divided from the adjacent section 125 38 by a score line 58, the ends of which continue into the score lines 56. The section 57 is divided by diagonally arranged score lines 59, on which the section is folded upon itself, as shown in Fig. 4, and when so 130

folded is swung down over the flaps 19, 19, whereupon the lid or cover 13 is swung down over the parts to close the box. The section 57 is further divided at the edge 42 and between the diagonal score lines 59 by a score line 60, which enables the section 57 when folded upon itself, as shown, to form a tapered flap to be provided with a marginal tongue 61, adapted to be inserted between the front wall 16 of the box and the folded portions of the lining sheet. The opposite section 39 is provided with a like score line 62, whereby the section may be folded back on itself, to prevent the section from overlapping the section 38, as shown in Fig. 4. The lining sheet 33 may be scored in the manner indicated by the dotted lines in Fig. 2, or it may be laid flat and unscored on the flat blank of the box and in setting up the box the lining sheet will be folded with the parts of the box on lines as indicated by the dotted lines in said Fig. 2. By folding the lining sheet in the manner described, it will be noted that the bakery products packed in the box are completely enveloped within such sheet and protected thereby from contact with the walls of the box and thereby maintained in a crisp and fresh condition at all times. Furthermore, the lining sheet is interfolded between the several end flaps of the box so that such flaps serve to lock the lining sheet in the box and prevent displacement thereof during packing of the box, as well as during removal of the products therefrom.

Although I have shown and described one form of box and lining sheet embodying the features of my invention, yet it is to be of course understood that the several details of construction and arrangement of parts shown may be variously changed and modified without departing from the spirit and scope of my invention, and I do not wish to be limited to the exact details of construction and arrangement of parts illustrated, except as pointed out in the annexed claims.

I claim as my invention:

1. A container having connected bottom and side walls, the latter being provided at the ends thereof with flaps adapted to overlap and form the end walls of said container, one of the end flaps at each end of the container being provided with a notch opening outward through one of the longitudinal edges of said flap, and the other end flap at each end of the container being provided with integral parts adapted to interlock for holding the tongue from being swung out of the notch.

2. A relatively shallow container having connected bottom and side walls, the latter being provided at the ends thereof with

flaps adapted to overlap and form the end walls of said container, one of the end flaps at each end of the container being provided with a notch opening outward through one of the longitudinal edges of said flap and with the base of said notch located substantially midway between the longitudinal edges of said flap, and the other end flap at each end of the container being provided with a locking tongue adapted to be inserted into said notch, and the notch and tongue at each end of the container being provided with integral parts adapted to interlock for holding the tongue from being swung out of the notch.

3. A container having connected bottom and side walls, the latter being provided at the ends thereof with flaps adapted to overlap and form the end walls of said container, one of the end flaps at each end of the container being provided with a notch opening outward through one of the longitudinal edges of said flap; one of the edges of said notch being continued into the body of the flap beyond the base of the notch to form a locking projection at the base of said notch, and the other end flap at each end of said container being provided with a locking tongue adapted to be inserted into said notch, one edge of said last named flap being extended beyond the base of said tongue for forming a locking shoulder adapted to engage the locking projection of said notch for holding the tongue from being swung out of the notch.

4. A foldable box or carton having connected bottom and side walls, the latter being provided at the ends thereof with flaps adapted to overlap and form the end walls of said box, the bottom wall being provided at each end thereof with a flap adapted to be folded between the end flaps on the side walls, the innermost end flap at each end of the box being provided with a notch opening outward through one of the longitudinal edges of said flap, the outermost end flap at each end of the box being provided with a locking tongue adapted to be inserted into said notch, and the intermediate end flap at each end of the box being cut away opposite the notch in the innermost end flap, and the notch and tongue at each end of the box having integral parts adapted to interlock for holding the tongue from being swung out of the notch.

5. A foldable box or carton having connected bottom, side and top walls, the bottom and side walls being provided at the ends thereof with flaps adapted to overlap and form the end walls of the box, said end flaps being provided with interlocking means adapted to lock said flaps together, the flaps on the bottom wall being folded between the flaps on the side walls, and a lining sheet in said box, adapted to envelop the articles packed therein, said lining sheet being made

from a single sheet of sheet material and adapted to be folded to have a section extending over the inner surfaces of all of the walls of the box and having a folded section 5 at each end of the box, said folded section extending over the upper and lower edges of the innermost end flap and being doubled upon itself so as to have one portion between the innermost and intermediate end flaps and another portion between the intermediate and outermost end flaps and extend- 10

ing over the upper edge of the intermediate end flap.

In testimony that I claim the foregoing as my invention, I affix my signature in the 15 presence of two witnesses, this 3rd day of October, A. D. 1917.

FRANK B. DAVIDSON.
